GYMNASIUM SPRINGBOARD

Bruce C. Sidlinger, Cedar Rapids, Iowa

Application February 7, 1949, Serial No. 74,939

5 Claims. (Cl. 272—65)

1

This invention relates generally to gymnastic equipment of the trampolin type tumbling mat and more particularly to a collapsible spring-board structure.

Gymnasium springboards available in the past have always been heavy and bulky and not sufficiently "springy" to be popular. Professional acrobats have need of a small, collapsible and sturdy device to assist them in bounding onto larger equipment or to the backs of circus animals.

It is a general object of my invention to provide a gymnasium springboard structure which is light weight but strong and achieves resilience far superior to the conventional type device for this purpose.

It is a further object of my invention to provide a gymnasium springboard which will fold up compactly for storage or transporting from place to place.

It is still another object of my invention to provide a gymnasium springboard which is easily set up and is self locking, requiring no bolts or special devices which must be adjusted to secure the device in its usable condition.

It is still another object of my invention to provide a gymnasium springboard which may be easily collapsed by applying pressure with the user's foot in the proper place.

It is still another object of my invention to provide a gymnasium springboard which may be inclined and means thereon for varying the angle of inclination.

It is still another object of my invention to provide a gymnasium springboard which is of simple design and constructed of common materials so as to be relatively inexpensive to produce and easy to maintain.

It is still another object of my invention to provide a gymnasium springboard which is small in size, the take-off surface and its supporting frame being reduced to a minimum compatible with safety.

These and other objects of the invention will be readily understood by reference to the accompanying drawings and following specification, wherein is disclosed a preferred exemplary embodiment of the invention.

In general, the present invention is directed to a foldable gymnasium springboard comprising a two-part frame, means, including hinges, for pivoting the two parts of the frame together and locking them in unfolded position, a resilient take-off surface carried by said two-part frame, a pair of short legs carried by one part of said frame, a pair of longer legs pivoted to the other

2

part of said frame, and flexible tension means interconnecting said pairs of legs. In the preferred embodiment shown, there is included a two-part frame, means forming a toggle joint hingedly connecting said two-part frame, for holding the two parts of the frame in the same plane when extended, the pivot of said toggle joint being below the dead center of said frame when extended, a pair of short legs secured to one of said frame members, a pair of longer legs variable in length and pivoted to the other of said frame members, flexible tension members interconnecting said pairs of legs, said pairs of legs converging upwardly when the springboard is unfolded to position the unfolded frame, at an incline, whereby a downward pressure on the uppermost edge of the upper frame will cause the toggle to break upwardly for folding.

In the accompanying drawings:

20 Fig. 1 is a plan view of a gymnasium springboard constructed in accordance with a preferred embodiment of my invention;

Fig. 2 is a side elevation view of the device illustrated in Fig. 1, broken away in part to show 25 how the stretched, take-off surface material exerts a force to hold the device locked in normal operating position;

Fig. 3 is a side elevation view of the device illustrated in Fig. 1 and Fig. 2 as it appears when 30 it is just starting to fold and showing how the tension of the rubber shock cord which supports the take-off surface material assists in folding the device after the line of force is below the frame joint, and

Fig. 4 is a side elevation view of the device 35 illustrated in Figs. 1, 2 and 3 as it appears in the completely folded position.

Referring now to the drawings in which like reference numerals refer to like parts; a take-off surface 10, preferably woven of parachute strap webbing, is fitted on its edges with a continuous rope 11 inserted in the looped ends of the said webbing. Take-off surface 10 is resiliently supported by a continuous length of rubber shock cord 12 woven between rope 11 and heavy wire loops 13. Wire loops 13 are fastened, preferably by welding, to frame 14 which is of tubular steel or the like. Frame 14 is formed of two U-shaped parts 14a and 14b adapted for folding by hinges 15 at points 15P and is slightly arched outwardly at each side for increased strength.

One pair of tubular supporting legs 16 are rigidly connected to the underside of the frame part 14b, preferably by welding, and preferably 55 reinforced, as by frame 17. Another pair of tub-

ular legs 18 are joined, preferably by welding, to a sleeve 19. The sleeve 19 is adapted to be pivotally mounted over frame part 14a. Legs 18 are provided with telescopic extension members 20 which are locked in any extended position by lock screws 21. The lower ends of legs 16 and extension members 20 are preferably provided with friction foot pads 22, such as rubber brake-pedal type pads.

The legs 16 and 18 are joined adjacent their base portions by a pair of flexible, non-resilient tension members 23, preferably in the form of chains, as shown. The chain members 23 serve to limit the outward movement of the legs 18 by rotation of the sleeve 19 around the frame portion 14a. Said chain members 23 also provide proper resistance against outward relative movement of the legs 16 and 18 when collapsing force, shown by arrow 24 in Fig. 3, is applied. Chain members 23 are also used for securing the apparatus in its compactly folded and locked condition as shown in Fig. 4. In this position, the chain members 23 may be held in tension by positioning the chains 23 in the angular hook portion 25 defined by the hinge 15 and abutment 25 ends of the frame members 14a and 14b.

In use, the downward loading on take-off surface 10 is resisted by the links or chain members 23. This resistance acts in conjunction with the slope of legs 16 and 18 to exert a force which keeps the frame locked in the desired set-up position. This effect is further influenced toward the same end by offsetting pivot points 15P below the dead center line CL of the tubular frame 14.

The pivots 15P of the hinges are positioned below the planar or lateral dead center line CL of the two-part frame members when fully extended, as shown in Fig. 2. This relative arrangement of the pivots 15P below the dead center line CL, and therefore below the longitudinal axis LA of the sleeve 19 which is shown in the same plane as the center line CL, enables the collapsing movement to take place by application of the downward force shown by arrow 24.

Thus, the present structure may be readily collapsed by the user by applying downward pressure, as by means of the user's foot, on the sleeve 19, as indicated by the arrow 24. This movement causes the frame to break upwardly at the hinge points 15, the legs 16 and 18 being held against outward relative movement at the points where they are joined by the tension members 23. As soon as the frame has been broken upwardly at the hinge points, the force of the resilient tensioned shock cord is sufficient to complete the collapsing movement of the structure as shown in Figs. 3 and 4. It should be further noted that hinges at points 15 are preferably not equidistant between the frame ends thereby allowing more compact folding, as shown in Fig. 4.

While I have shown a preferred embodiment of my invention, it will be understood that various modifications may be made therein without departing from the spirit and scope of the invention and I intend to include all such modifications as covered by the following claims.

I claim:

1. A foldable gymnasium springboard, comprising

ing in combination, a two-part, generally rectangular frame, including two generally U-shaped members, the arms of which are respectively abutted at their ends, means including a hinge positioned below the level of the abutting ends of the said arms for pivotably joining said U-shaped members whereby said U-shaped members lie in the same plane when the ends of said arms are in abutting relationship and the pivoting motion from the single plane is only upward, a flexible take-off surface resiliently supported within said frame, a fixed pair of legs attached to and supporting one of said frame members, a pair of legs pivotably attached to the base of the other of said U-shaped members and extending downwardly and outwardly therefrom and defining an angle greater than 90° with said frame, and flexible tension means interconnecting said pairs of legs.

2. A foldable gymnasium springboard, comprising in combination, a two-part, generally rectangular frame, including two generally U-shaped members, the arms of which are respectively abutted at their ends, means including a hinge positioned below the level of the abutting ends of said arms for pivotably joining said U-shaped members whereby said U-shaped members lie in the same plane when the ends of said arms are in abutting relationship and the pivoting motion from the single plane is only upward, a flexible take-off surface resiliently supported within said frame, a fixed pair of short legs attached to and supporting one of said frame members, a pair of relatively longer legs pivotably attached to the base of the other of said U-shaped members and extending downwardly and outwardly therefrom and defining an angle greater than 90° with said frame, and flexible tension means interconnecting said pairs of legs.

3. The device as set forth in claim 2 wherein said pivoted longer legs are provided with telescopic means for varying the length thereof.

4. The device as set forth in claim 2 wherein said pair of short fixed legs are integrally secured to the frame member and including a pair of braces integrally secured respectively to both the same frame member and said fixed legs to form a rigid triangular support unit.

5. The device as set forth in claim 2 including a sleeve fixedly carrying said pivoted longer legs, said sleeve being rotatably mounted on the base of one of said U-shaped members whereby both of said legs pivot in unison.

BRUCE C. SIDLINGER.
